TOY ROCKET GUN

Leon H. Amdur, Brooklyn, N. Y.

Application June 24, 1946, Serial No. 678,803

21 Claims. (Cl. 124—11)

1

This invention, which relates to toys, has for its object the creation of a toy rocket gun which may be safely used by children and yet will be realistic in operation, and which may be produced at a reasonable market price.

Another object of the invention is to provide a toy rocket gun which may be operated, both in the propulsion of the rocket from the barrel and in the flight of the rocket, by air charged into the rocket before the gun is "fired" (i. e., before the rocket is released) and which exhausts from an open tube at the rear of the rocket; in this respect the toy realistically simulates a real rocket. A further object is to make the operation more realistic by providing means for producing a cloud or smoke which escapes with the compressed air through the exit tube to leave a trail of smoke behind the rocket. An allied object is to produce this cloud or smoke by means including the use of chemicals or inert substances which are harmless. A further object is to add to the realistic operation of the novel toy by providing means associated with the said exit tube for producing a whistle or other sound effect as the charged air flows therethrough in flight of the rocket.

Viewed from another aspect, the object of the invention is to provide a toy rocket gun, operated by air compressed into the rocket, which, by the construction of the barrel, the rocket and associated parts, will effectively propel the rocket from the barrel and maintain it in flight for substantial distances, but which will not have sufficient momentum to injure either the person or furniture or the room. A further object is to provide a toy rocket gun which may be aimed at designated targets and which will call for skilful, as distinguished from haphazard, operation in causing the rocket to hit the designated target. An allied object is a toy rocket gun having a barrel which is angularly adjusted to change the angle of elevation of the projected rocket. Another allied object is a toy rocket gun having an air-charged rocket, the flight of which may be predetermined by the pressure of the air charge and by other manipulations at the barrel (as will be described).

For the attainment of the foregoing and such other objects as may appear or be pointed out herein I have shown two embodiments of my invention in the accompanying drawing, wherein

Fig. 1 is a side view of the toy rocket gun employing an air bulb for charging, the barrel and most of the rocket being in section;

Fig. 2 is a front view of the toy rocket gun of Fig. 1, looking at the forward end of the rocket in its barrel;

Fig. 3 is a side view of the toy rocket gun employing a compressor for charging, the head end of the compression being in section and a portion of the frame broken away; and

Fig. 4 is a rear view of the toy rocket gun of Fig. 3, looking at the closed end of the barrel.

2

Referring first to Figs. 1-2, the toy rocket gun comprises a frame having a base 9 and a pair of upstanding side plates 8, 8, a barrel 10 closed at its left end 11 and open at its right end, and an air-tight rocket 20. Base 9 and its side plates 8, 8 are stamped from sheet metal, the upper or distal ends of side plates 8, 8 being pierced by aligned apertures 7, 7. Barrel 10, which is also made of sheet metal, has arcuate flanges or segments 17, 17', see Fig. 1, tongued out of the sheet metal at diametrically opposite sides of the barrel, see Fig. 2, and located substantially at the midpoint of the barrel length, Fig. 1. Arcuate flanges 17, 17' fit in the aligned apertures 7, 7 of the side plates 8, 8, for pivotally mounting the barrel so that the angle of elevation may be changed as desired; this fit is tight so that the barrel will be frictionally maintained in the desired inclination.

Rocket 20 is also made of sheet metal but must be made air-tight, and is preferably made of thin gauge, light material to reduce its weight. Rocket 20 has the nose contour 22 of a rocket or projectile and a similar rear contour including rear tube 21 and sloped end 23. Sloped end 23 terminates in an aperture 24 into which open tube 21 is forced so that portion 21 extends rearwardly of the rocket and a portion 25 extends interiorly of the rocket. The tube is fitted securely in aperture 24 and made air-tight by soldering or the like. Near its forward end rocket 20 has an annular recessed shoulder 29 latched by a spring-pressed pin 19 on barrel 10 to hold the rocket within the barrel.

Means are provided for closing the open end 26 of rocket tube 21 when the rocket is in its barrel and is being charged with air. As shown in Fig. 1, this means comprises a rubber disc 12 and a metal disc 13 each of a diameter somewhat less than the internal bore of barrel 10, and a coil compression spring 14. In assembling, spring 14 is first inserted, followed by the metal disc 13 and then by the rubber disc 12. The discs are then forced inwardly to compress the spring and to move rubber disc 12 inwardly of a pair of tabs 16 tongued-out of the barrel, whereat tabs 16 are turned inwardly as shown to furnish a pair of stops against which rubber disc 12 abuts and is forced by compressed spring 14. The rubber may be smaller in diameter or thinner, and adhered to the outer face of metal disc 13.

Rocket 20 is inserted in the open end or mouth of barrel 10 with its rear tube 21 foremost. The rocket may be freely inserted, i. e., without force, until open end 26 of rocket tube 21 abuts the rubber disc 12. To complete the insertion, the rocket must be forced inwardly against the compression spring 14, its rear tube 21 moving discs 12 and 13 inwardly away from stops 16. This inward forcing of the rocket is continued until its annularly recessed shoulder 29 arrives at a point at which latch pin 19 snaps in front of the shoulder to

hold the rocket in latched (and fully inserted) position, as shown in Fig. 1. Rubber disc 12 pressed against open end 26 of rocket tube 21 by compressed spring 14, the rocket being held by latch pin 19, furnishes a closure for the open tube during the time the rocket is being charged with air under pressure (as will be subsequently described). In addition, the compressive force of coil spring 14 adds to the propulsive force imparted to the rocket by the reactive force of the compressed air blowing out of exit tube 21 when the rocket is released (by withdrawing latch pin 19, as will be described). Lastly, the provision of the compression spring and a "floating" rubber disc 12 will provide an effective closure for exit tube 21 even where the tube had not been precisely positioned in aperture 24 to provide a rear tube extension of a predetermined dimension.

The stop lugs 16 may be omitted and the discs secured to the coil spring anchored to closed end 11 of the barrel. In some cases the rubber disc or a rubber pad may be adhered directly on closed end 11 of the barrel, or omitted entirely and the open end 26 of exit tube 21 abutted against closed end 11.

Latch pin 19 is housed within a tube 6 which is force fitted in a hole 5 pierced at an upper point near the open end of barrel 10. The upper end of latch pin 19 extends upwardly beyond tube 6 to furnish an exposed portion 15 which may be grasped for withdrawing the pin. The upper end 4 of tube 6 may be closed or crimped-in to provide a bearing for the latch pin. Latch pin 19 has a small cross-pin 39, the ends of which are received in a pair of diametrically opposite elongated slots 3 in tube 6. A coil compression spring 2 is interposed between closed end 4 of the tube and cross-pin 39 for forcing latch pin 19 downwardly to protrude its lower end into the barrel. This end of the latch pin has a bevel 18 facing the open end of the barrel, so that the rocket, more particularly its inclined rear portion 23, will cam the latch pin outwardly as the rocket is being inserted. The latch pin is so positioned that, when the rocket is fully inserted and coil spring 14 compressed to the proper extent, it will snap in front of annularly recessed shoulder 29 of the rocket, as shown, to latch the rocket in place while being charged with air.

A short, narrow tube 30 is force fitted in a hole in the rocket near its forward end 22 and a short-distance rearwardly of annularly recessed shoulder 29. A short portion 31 of the tube extends exteriorly of the rocket, and the juncture between the tube and the outer surface of the rocket is made air-tight by soldering or the like. The end 32 within the rocket is closed by crimping, swaging, soldering or the like. The portion of the tube within the rocket is pierced by an opening 33 in the tube wall near the inner surface of the rocket. A strip 34 of resilient material is secured, as by soldering, at the upper, closed end 32 of the tube, with the lower or distal end portion of strip 34 closing tube opening 33. Tube 30 thus constitutes an inlet for charging the rocket with air under pressure and a check valve for preventing escape of the air compressed into the rocket. One end of a rubber tubing 35 is slipped on exterior portion or nipple 31 and air forced under pressure through opening 33 of the tube, the air pressure flexing the distal end of resilient strip 34 away from the opening to permit the air to enter the rocket. When the air pressure in rubber tubing 35 drops or when the tubing is removed, the resilient and flexed strip

34 will return to normal position closing opening 33 and will be held in closing position by the air pressure built up within the rocket.

The barrel 10 is cut away at its open end for the major portion of its periphery to leave an arcuate overhang 36 at the upper part of the barrel mouth. The aforementioned hole 5 for latch tube 6 is provided in this arcuate overhang 36. Arcuate overhang 36 extends rearwardly of the barrel, Fig. 1, to a point where the major portion 37 of the barrel periphery terminates. As clearly shown in Fig. 2, terminal edge 37 of the barrel occupies the major portion of the full circle, leaving a relatively small arcuate terminal edge (arcuate overhang) 36. And as shown in Fig. 1, major terminal edge 37 of the barrel mouth is somewhat to the rear of the position occupied by air inlet 31 of the rocket when the rocket is latched in the barrel. By cutting away the open end of the barrel in this manner and by extending recessed shoulder 29 of the rocket annularly around the rocket, the rocket may be inserted in the barrel with its inlet nozzle 31 disposed at any angle (i. e., within the large angle, which is the major portion of a full circle, subtended by recessed terminal edge 37 of the barrel mouth).

A suitable chemical which will produce smoke or fumes by the action of air or a suitable inert substance, such as powdered chalk, talc or the like, which will mix with the air to produce a cloud, is inserted through rear exit tube 21, into the interior of the rocket, indicated by reference character 1. The portion 25 of the rear exit tube extending interiorly of the rocket, by spacing the tube opening away from the interior surface of the rocket, prevents the material 1 from directly entering the exit tube 21 in any position of the rocket in flight or in barrel 10, inclined at the desired angle of elevation. The air forced under pressure into the rocket will react with material 1 or mix therewith to form a cloud or smoke which will pass through the rear exit tube with the flow of air therethrough when the rocket is released for propulsion and flight, and leave a trail of smoke behind the rocket, to realistically simulate an actual rocket. It should be noted that opening 33 of tube 30 is close to the interior surface of the rocket so that the in-flow of air under pressure through opening 33 will sweep along the interior surface of the rocket to effectively agitate, mix with or interact with, the substance 1 deposited along the interior surface.

The end of the interior portion 25 of the exit tube is beveled to a fine point to provide a sharp circular edge 27 at the entrance to the exit tube. As the air under pressure flows past sharp edge 27 into the exit tube, a shrill sound or whistle is emitted as the rocket leaves barrel 10 and continues in flight. Other means may be provided for producing a sound effect, such as tiny holes 28 pierced through interior tube portion 25, or a narrow strip 38 formed by slitting the thin wall of the tube at its end portion, which strip acts as a reed.

The rocket may be charged with air in any suitable manner; in Fig. 1, this is an air bulb 40 connected by rubber tubing 35 to inlet nozzle 31. Air bulb 40 may be of the type having an opening 41 at one end over which the thumb is held when the bulb is compressed and removed when the bulb is released and extended by air entering opening 41; or it may be of the type having a check inlet valve. Instead of the air bulb an air pump may be used, similarly connected to the rocket inlet 31 by rubber tubing. After the rocket

is sufficiently charged with air, rubber tubing 35 is slipped off rocket nozzle 31 and latch pin 19 withdrawn to release the rocket for propulsion and flight.

In Figs. 3-4 the toy rocket gun is implemented with a simple air compressor. The base 9' of the frame is somewhat longer and has a similar pair of side plates 8', 8' at the upper, distal ends of which barrel 10 is pivotally mounted in the manner described above with reference to Figs. 1-2. Underlying barrel 10 to provide sufficient clearance for pivoting the barrel and close to base 9' is an air cylinder 42 provided with a pair of diametrically opposite, laterally extending fins 43, 43, which are slidably received in a pair of elongated slots 53, 53 in side plates 8', 8' of the frame, whereby air cylinder 42 may be reciprocated. Fins 43, 43 each have a laterally projecting pin 44 received in slots 54, 54 at the distal ends of a pair of fork arms 51, 51 which together with a common handle 52 constitute a bifurcated lever 50. Forks 51, 51 are disposed outwardly of side plates 8', 8', Fig. 4, and are pivotally mounted, at the common pivotal mounting of barrel 10, at the upper, distal ends of the side plates. For this purpose, the forks 51, 51 each have an inwardly directed protuberance 57 which is received within the hole defined by the arcuate flanges or segments 17, 17' tongued out of the barrel. The bend 55 of bifurcated lever 50 is sufficiently above the barrel 10 to provide clearance for angling the barrel. Handle 52 of the bifurcated lever is manipulated back and forth to turn the lever and reciprocate air cylinder 42.

The head end 45 of the cylinder has a central aperture 46 for a piston rod 47 and may be provided with suitable packing (not shown) to prevent air leakage from the air cylinder as it is reciprocated relatively to piston rod 47. The latter is secured, as by nuts 48, 48, at its outer end to an upstanding lug 49 tongued out of base 9' of the frame. The inner end of piston rod 47 is secured, as by screw threads, to a piston 56 which has a leather cup 58. In this manner piston 56 is held stationary as air cylinder 42 is reciprocated. Air is admitted, upon the suction stroke of the cylinder (to the right, Fig. 3), into the head end of the cylinder through an aperture 59 in cylinder head 45. A strip 69 of resilient material is secured at its lower end to cylinder head 45 with its upper, distal portion covering aperture 59 and provides a check valve allowing ingress of air upon the suction stroke and closing aperture 59 when the air cylinder is moved leftwardly, Fig. 3, on the pressure stroke. A short tube or nipple 61 is provided at the head end of the air cylinder and is connected by rubber tubing 35 to the inlet nozzle or nipple of the rocket.

The closed end 11 of barrel 10 is provided in Figs. 3-4 with a centrally located threaded member 62 which may be turned to abut the inner end of screw member 62 with the discs 12, 13 within the barrel to force rubber disc 12 more tightly against the open end 26 of rocket exit tube 21, see Fig. 1, where it is desired to build up the air pressure within the rocket to a higher degree than would be permitted by coil spring 14.

Inlet nozzle 31, Figs. 1-2, extends but a short amount beyond the rocket. But to avoid the possibility of this being broken off, the inlet arrangement of Fig. 3 may be used, in which tube 30' is flush with the rocket wall and is larger than tube 30 of Fig. 1 to provide an inner bore 62 which will frictionally receive one end of a nipple 64 the other end of which is permanently se-

cured in rubber tubing 35. Nipple 64 has an opening or openings 63 which align with aperture 33 of tube 30'. The outer surface of nipple 64 and the inner bore 62 of tube 30' may have a rib and groove arrangement to compel the nipple to be properly inserted in tube 30', with its opening 63 aligned with aperture 33 of the tube. When the rubber tubing is disconnected from the rocket, its nipple 64 is simply withdrawn from the bore 62 of tube 30', leaving nothing to project from the rocket surface. Nipple 64 may be designed so that but a short length thereof enters the bore of tube 30'; in this case the nipple need not have a side opening alignable with aperture 33 of the tube. A bayonet joint may be used with either the long or the short nipple; or the bore 62 may be threaded at its opening and the nipple threaded at its end to provide for a screw connection of the nipple.

I claim:

1. A toy rocket gun comprising a frame, a barrel open at one end pivotally mounted on the frame, an air-tight rocket having a central opening at its rear end and an annularly recessed shoulder near its front end, a rubber disc and a metal disc of slightly smaller diameter than the bore of the barrel near the closed end of the barrel with the rubber disc outermost, lugs tongued-in from the barrel, a compression coil spring between the closed end of the barrel and said metal disc for forcing the discs outwardly with the rubber disc abutting the lugs, the said rocket being inserted at the open end of the barrel with its said rear opening abutting the rubber disc, a spring-pressed latch pin outwardly beveled and positioned at the open end of the barrel to snap in front of the said recessed shoulder of the rocket upon a full insertion thereof in the barrel, the rear end of the latched rocket forcing the rubber disc rearwardly against the compression spring to establish an air-tight closure at the said rear opening of the rocket, an inlet fitting having a pressure check tightly secured in the rocket, and means connectable with said inlet fitting for charging the rocket with air pressure.

2. A toy rocket gun comprising a frame, a barrel open at one end mounted on the frame, an air-tight rocket having an open rear tube and a recessed shoulder near its front end, a rubber disc, a metal disc and a compression coil spring at the closed end of the barrel with the rubber disc outermost, said rocket being inserted at the open end of the barrel with the open end of its said rear tube abutting the rubber disc, a spring-pressed latch pin positioned at the open end of the barrel to snap in front of said recessed shoulder of the rocket upon a full insertion thereof in the barrel, the rear tube of the latched rocket forcing the rubber disc rearwardly against the compression spring to establish an air-tight closure for the opening of the rear tube, an inlet fitting having a check valve secured in the rocket, and means connected to said inlet fitting for forcing air under pressure into the rocket.

3. A toy rocket gun comprising a frame, a barrel open at one end mounted for angular adjustment on the frame, a rocket having an open tube at its rear and a recess near its front end, a disc and a compression coil spring at the closed end of the barrel, said rocket being inserted at the open end of the barrel with its said rear tube abutting the disc, a latch pin near the open end of the barrel received in said recess of the rocket upon a full insertion of the rocket, the rear tube of the rocket forcing the disc rearwardly to com-

press the spring, means for charging the rocket with air pressure, the said compressed coil spring establishing a closure for the opening of the rear tube of the rocket, and manual means for withdrawing the said latch pin to release the rocket to propulsion by the said compressed spring and the air pressure within the rocket reacting through its rear tube.

4. A toy rocket gun comprising a barrel open at one end, a frame including a base for mounting the barrel in raised position relative to the base and for angular adjustment of the barrel, an air-tight rocket having a central, open tube at its rear and a recess in its surface, a rubber disc secured to the closed end of the barrel with the end of its said rear tube abutting the said rubber disc, a latch pin on said barrel spring pressed inwardly to be received in said recess of the rocket when inserted in the barrel with its said rear tube pressed against the rubber disc, a check valve inlet in the rocket, and means couplable to said inlet for placing the rocket under air pressure, said latch pin having an accessible portion for manually releasing the latch pin.

5. A toy rocket gun comprising a frame having a base and a pair of upstanding side plates, a barrel open at one end pivotally mounted at the upper ends of said side plates, an air-tight rocket having a rearwardly extending tube portion open at its rear end and an annularly recessed shoulder near its front end, said rocket being inserted at the open end of the barrel with the open end of its tube portion abutting the closed end of the barrel, means for charging the rocket with air under pressure, and a manually releasable, spring-pressed latch pin positioned at the open end of the barrel to snap in front of the said recessed shoulder of the rocket to retain it in the barrel against the force of the air pressure within the rocket.

6. A toy rocket gun comprising a barrel open at one end, an air-tight rocket having a rearwardly extending tube portion open at its rear end, said rocket being inserted at the open end of the barrel with its said tube portion at the closed end of the barrel, a short tube tightly secured in the said rocket with a portion extending exteriorly thereof, the interior portion of the tube being closed at its end and provided with an opening in its wall, a strip of resilient material secured at one end to the said interior tube portion with its distal end portion closing the said tube opening, and means connecting to the said exterior portion of the said tube for forcing air under pressure into the rocket.

7. A toy rocket gun comprising a barrel open at one end, an air-tight rocket inserted at the open end of the barrel and provided with an annularly recessed shoulder near its front end, an inlet nozzle extending laterally from the rocket at a point rearward of its said recessed shoulder, means connectable with said inlet nozzle for charging the rocket with compressed air, the barrel being cut away at its open end for the major part of its periphery leaving an upper, arcuate overhang extending to a point outward of the annularly recessed shoulder of the inserted rocket, a spring-pressed latch pin disposed on the said arcuate overhang of the barrel in position to snap in front of the said annularly recessed shoulder of the inserted rocket, said arcuate overhang extending to a point rearward of the said inlet nozzle of the inserted rocket, whereby the rocket may be inserted in

the barrel for latching with its inlet nozzle in any angular position within the said major part of a circle.

8. A toy rocket gun comprising a barrel open at one end, an air-tight rocket inserted at the open end of the barrel, a frame for pivotally mounting the barrel to change the elevational angle of the rocket, said rocket having a central rear opening, an open tube tightly secured in said opening with a rearwardly extended portion and a portion extending interiorly of the rocket, a cloud-making substance contained within the rocket, the said interior portion of the tube preventing escape of the said substance in any elevational angle of the rocket, an inlet for admitting air into the nozzle, and means connected to said inlet for flowing air under pressure into the rocket, said in-flow of air agitating the said substance to produce a cloud within the rocket.

9. A toy rocket gun comprising a barrel open at one end, an air-tight rocket inserted at the open end of the barrel, a frame for pivotally mounting the barrel to change the elevational angle of the rocket, said rocket having a central rear opening, an open tube tightly secured in said opening with a rearwardly extended portion and a portion extending interiorly of the rocket, a cloud-making substance contained within the rocket, the said interior portion of the tube preventing escape of the said substance in any elevational angle of the rocket, a small tube tightly secured in the rocket with a portion extending exteriorly thereof, the interior portion of the tube being sealed at its end and provided with an opening in its wall, a strip of resilient material secured at one end to said interior tube portion with its distal end covering said opening, means attached to said exterior tube portion for flowing air under pressure into the rocket, said opening in the tube wall being close to the interior surface of the rocket to direct the said in-flow of air along the said surface to mix with the said cloud-making substance.

10. A toy rocket gun comprising a barrel open at one end, an air-tight rocket inserted at the open end of the barrel, a frame for pivotally mounting the barrel, a check inlet valve secured in the rocket wall, an air bulb connectable to said valve for charging the rocket with air under pressure, said rocket having a rear exit aperture wherethrough the air charged within the rocket escapes and maintains the rocket in flight.

11. A toy rocket gun comprising a frame having a base and a pair of upstanding side plates, an open mouth barrel pivotally mounted at the distal ends of said side plates, an air-tight rocket inserted in said barrel and having an inlet valve, an air cylinder underlying said barrel and having an outlet nipple at its head end, rubber tubing connecting said inlet valve of the rocket and outlet nipple of the air cylinder, said cylinder having a pair of diametrically opposed fins, the said pair of side plates of the frame having near their proximal ends elongated slots for slidably receiving the said fins of the cylinder, a bifurcated lever pivotally mounted at the distal ends of the side plates with its handle centrally disposed above and clearing the said pivotally mounted barrel, the two forks of the bifurcated lever being disposed outwardly of the pair of side plates and provided with slots at their distal ends, the said pair of fins each having an outwardly extending pin receivable in the said slots of the lever forks, the head of the air cylinder having

a central aperture and the said frame base having an upright lug spaced from said cylinder head, a piston within the air cylinder and a piston rod passing through said aperture of the cylinder head and connected at its outer end to said frame lug, the inner end of the piston rod being connected to said piston to maintain it in stationary position relative to the reciprocating cylinder.

12. A toy rocket gun comprising a frame having a base and a pair of upstanding side plates, an open mouth barrel pivotally mounted at the distal ends of said side plates, an air-tight rocket inserted in said barrel and having an inlet valve, an air cylinder underlying said barrel and having an outlet nipple at its head end, rubber tubing connecting said inlet valve of the rocket and outlet nipple of the air cylinder, said cylinder having a pair of diametrically opposed fins, the said pair of side plates of the frame having near their proximal ends elongated slots for slidably receiving the said fins of the cylinder, a bifurcated lever pivotally mounted at the distal ends of the side plates with its handle centrally disposed above and clearing the said pivotally mounted barrel, the two forks of the bifurcated lever being disposed outwardly of the pair of side plates and provided with slots at their distal ends, the said pair of fins each having an outwardly extending pin receivable in the said slots of the lever forks, and a piston held stationary within the reciprocating air cylinder.

13. A toy rocket gun comprising a frame having a base and a pair of upstanding side plates, an open mouth barrel pivotally mounted at the distal ends of said side plates, an air-tight rocket inserted in said barrel and having an inlet valve, an air cylinder underlying said barrel and having an outlet nipple at its head end, rubber tubing connecting said inlet valve of the rocket and outlet nipple of the air cylinder, said cylinder having a pair of diametrically opposed fins, the said pair of side plates of the frame having near their proximal ends elongated slots for slidably receiving the said fins of the cylinder, the head of the air cylinder having a central aperture and the said frame base having an upright lug spaced from said cylinder head, a piston within the air cylinder and a piston rod passing through said aperture of the cylinder head and connected at its outer end to said frame lug, the inner end of the piston rod being connected to said piston to maintain it in stationary position, and means for reciprocating the air cylinder relative to the stationary piston.

14. A toy rocket gun comprising a frame having a base and a pair of upstanding side plates, an open mouth barrel, pivot means at the distal ends of the side plates for mounting the said barrel, an air-tight rocket having an inlet inserted in said barrel, an air compressor underlying said barrel and having an outlet, rubber tubing connecting said inlet and outlet, a bifurcated lever mounted by the said pivot means at the distal ends of the side plates of the frame with its handle centrally disposed above and clearing the said pivotally mounted barrel, the two forks of the bifurcated lever being disposed outwardly of the pair of side plates and operatively connected at their distal ends to the said air compressor.

15. A toy rocket gun comprising a barrel open at one end, a frame including a base for pivotally mounting the barrel in raised position relative to the base, an air-tight rocket having an inlet inserted in said barrel, an air compressor on said base in underlying relation to said pivotally mounted barrel and having an outlet, rubber tubing connecting said inlet and outlet, and a lever pivotally mounted on said frame for operating the air compressor.

16. A toy rocket gun comprising a barrel open at one end, an air-tight rocket inserted at the open end of the barrel, said rocket having a central rear hole, an open tube tightly secured in said hole with a portion extending interiorly of the rocket, means for charging the rocket with air under pressure, said air exhausting through the said open tube at the rear of the rocket to propel the rocket from the barrel and maintain it in flight, and means associated with the said interior portion of the tube for emitting sound as the air exhausts therethrough.

17. The toy rocket gun according to claim 16 wherein the end of the said interior tube portion is beveled to present a sharp circular edge to the air entering the said tube, to furnish the said sound emitting means.

18. The toy rocket gun according to claim 16 wherein the said interior tube portion is pierced by minute holes to furnish the said sound emitting means, as the air passes therethrough into the said tube.

19. The toy rocket gun according to claim 16 wherein the said interior tube portion is slitted at the open end thereof to provide a narrow strip of the thin wall material which functions as a reed to the air entering the said tube, to furnish the said sound emitting means.

20. A toy rocket gun comprising a barrel having one end open, an air-tight rocket inserted in the said barrel, a tube closed at one end disposed within the rocket and secured to the wall thereof with its open end substantially flush with the outer surface of the rocket, an aperture in the wall of the tube, a strip of resilient material secured at one end to the tube with its distal portion closing the said aperture, means including a length of tubing for charging the rocket with air under pressure, and a nipple secured at one end in the said tubing, the other end of said nipple being receivable in the bore of the said tube within the rocket.

21. A toy rocket gun comprising a barrel open at one end, a rocket slidably receivable in the said barrel, a frame including a base for mounting the said barrel in an elevated position relative to said base and for pivotal movement of the barrel to change the angle of elevation of the rocket, a coil spring at the closed end of the barrel, said rocket being inserted at the open end of the barrel and forced inwardly to compress the said coil spring, said rocket having a recess presenting a shoulder, and a spring-pressed latch pin on the said barrel receivable in said recess of the rocket when the rocket is inserted in the barrel and the coil spring compressed, said latch pin having an accessible portion for withdrawing the same from abutment with the shoulder of the said rocket recess.

LEON H. AMDUR.
